UNITED STATES PATENT OFFICE.

WILHELM HASENBACH, OF MANNHEIM, GERMANY, ASSIGNOR TO VEREIN CHEMISCHER FABRIKEN IN MANNHEIM, OF MANNHEIM, GERMANY.

CALCINING OR DECOMPOSING FURNACE.

SPECIFICATION forming part of Letters Patent No. 726,911, dated May 5, 1903.

Application filed April 28, 1902. Serial No. 105,089. (No model.)

To all whom it may concern:

Be it known that I, WILHELM HASENBACH, a subject of the German Emperor, residing and having my post-office address at Chemische Fabrik Wohlgelegen, Mannheim, Germany, have invented certain new and useful Improvements in Calcining or Decomposing Furnaces, of which the following is a specification.

- 10 The construction of the mechanically-worked calcining or decomposing furnaces and the like, and especially those with stationary muffles and rotating agitators, have the drawback that their main components—viz.,
- 15 the muffle and the hearth and agitator, respectively—are liable to disarrange themselves in their respective positions, thereby giving rise to an interruption in the working of the plant owing to the agitator getting jammed.
- 20 The reciprocal displacement of muffle and agitator and the jamming of the latter thereby produced has in the hitherto-known constructions its cause in the fact that the brickwork of the oven is a constructional element which
- 25 serves as a bearer and as a point of support both for the muffle and for the agitator, such element having a tendency to become deteriorated in course of working by the fire-gases and the influence of the material to be
- 30 calcined.

For the above-explained reasons, among the numerous constructions of mechanically-operated calcining or decomposing furnaces only those with rotating hearth and stationary agitator have found practical use, because in this construction the hereinbefore-described drawbacks do not exist in so high a degree as in those with a stationary calcining-hearth and a rotating agitator.

- 35 The present invention now relates to a mechanically-operated muffle or calcining-oven in which the aforementioned drawbacks are obviated by a particular arrangement of the main organs of the apparatus, (the muffle and the agitator,) inasmuch as they are so rigidly united to each other that their relative or reciprocal displacement becomes an impossibility.
- 40 In the subjoined, Figure 1 represents a plan
- 45 of the oven, and Figs. 2 and 3 are vertical

sections thereof on the lines A B and C D of Fig. 1.

By means of a casting B the muffle and hearth A, respectively, are secured in an iron framework D and united to the latter. The casting B serves at the same time for bearing the shaft of the agitator. In this construction the brickwork plays no constructional part, but only serves as fire-channel and as means for maintaining the heat.

The main constituents of the mechanically-operated calcining-oven are the iron muffle or hearth A, the casting B, the agitator C, and the iron framework D.

The muffle A comprises the cup a with the hub b, the mantle c, and the cover d. The mantle c is provided with three cleaning-holes e, and the cover d with the depending scraper f, the inlet-pipe g, and the gas outlet or escape pipe g'.

The casting B serves for rigidly uniting the muffle A with the iron framework D, and by means of the stuffing-box h also acts as a guide for the shaft of the agitator.

The agitator C, driven by belting or by gearing from an electric motor, comprises the agitator-shaft or "King's rod" i, the hub k, which fits over and is supported on the hub b, the stirring-arms l, and the scrapers m.

The calcining material lifted by an elevator is fed into the hopper n and conveyed by the worm o through the pipe g into the muffle. Any material that may lodge on the agitator will be removed by the scraper f as the agitator is rotated beneath it.

Should the oven be intended to be used for producing sulfates, the pipe t may be employed for the admission of the required quantity of sulfuric acid. A continuous stirring of the calcining material is effected by the agitator, and the finished product is fed continuously into transporting-trucks through the exit-pipe p, provided with an automatic obturator q. The gases are sucked off through the pipe g'. The fire gases preferably first come in contact with the cover and the mantle of the muffle, pass downward through the openings r, then heat the cup, and finally pass through s to the chimney.

What I claim is—

95

100

1. A calcining or decomposing furnace comprising an iron framework, a hollow casting mounted on the framework for supporting the muffle and serving as a bearing for the shaft 5 of the agitator, a muffle supported on the casting and having an inner hub, an agitator within the muffle supported by the said hub, a shaft for the agitator having a bearing in the hollow casting, and means for operating the agitator, 10 substantially as described.

2. A calcining or decomposing furnace comprising an iron framework, a hollow casting mounted on the framework for supporting the muffle and serving as a bearing for the shaft

of the agitator, a muffle supported on the casting and having an inner hub, an agitator within the muffle provided with a hub fitting over the hub of the muffle, a shaft for the agitator having a bearing in the hollow casting, and means for operating the agitator, 15 substantially as described.

In testimony whereof I have signed my name to this specification in the presence of two subscribing witnesses.

WILHELM HASENBACH.
